CLAIM

The ornamental design for a pickle jar, as shown and described.

DESCRIPTION

FIG. 1 is a front, right, top perspective view of a pickle jar, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view.

The dashed broken lines in the figures are for the purposes of illustrating portions of the pickle jar and form no part of the claimed design.
